FILLING VALVE

Clyde D. Russell, Oakland, Calif., assignor to California Packing Corporation, San Francisco, Calif., a corporation of New York

Application August 7, 1944, Serial No. 548,410

8 Claims. (Cl. 226—116)

1

This invention relates to filling valves, that is, to means for adding a predetermined quantity of liquid to cans or bottles partially filled with fish, fruits or vegetables, or other foods which require a set or fixed quantity of liquid. Among the objects of my invention are:

First, to provide a filling valve of this character wherein the contents of the can is vacuumized prior to introduction of the liquid so that a substantial portion of the objectionable air content is removed.

Second, to provide a filling valve of this character wherein the liquid is added to the contents of the can while the vacuum therein is maintained, so that the liquid thoroughly and completely permeates the contents.

Third, to provide a filling valve of this character which may be readily and accurately adjusted to deliver various quantities of liquid to meet the needs for various sizes of bottles and cans, or the various foods contained therein.

With the above and other objects in view, reference is directed to the accompanying drawings, in which:

Figures 1, 2 and 3 are similar longitudinal sectional views through the filling valve, showing in Fig. 1 the initial position wherein the can to be filled has not as yet engaged the valve; showing in Fig. 2 the intermediate position wherein the can is being vacuumized; and showing in Fig. 3 the final position wherein the charge of liquid is introduced.

Fig. 4 is a fragmentary plan view from 4—4 of Fig. 1.

Fig. 5 is a fragmentary sectional view through 5—5 of Fig. 1.

Fig. 6 is a fragmentary sectional view through 6—6 of Fig. 3.

Shown fragmentarily in the drawings is a table 1 adapted to rotate about a vertical axis. The periphery of the table is provided with a vertical wall 2 so as to form therewith a vessel or container for the liquid such as oil, or fruit or vegetable juices which it is desired to place in the cans of food. A series of plunger barrels 3 is secured to the table 1 adjacent the wall 2. The table is provided with extensions 4 which are concentric with the plunger barrels 3. Mounted at the top of each plunger barrel is a sleeve 5 which is provided with a flange 6 at its lower end to form a closure for the plunger barrel. A bleeder port 7 is provided in the flange 6.

A hollow plunger 8 is mounted within the plunger barrel 3. The plunger 8 is closed at its lower end by a partition, and its upper end is

2

provided with a cap 9 in which is provided a bleeder port 10. A stem 11 extends upwardly from the cap 9 through the sleeve 5, and its upper end is provided with a spider wheel 12. The spider wheel is provided with several radiating arms 13.

Suitably positioned at one side of the table 1 is a bracket 14 having a laterally extending trip arm 15 positioned so as to engage the spider wheel 12 and rotate it through a predetermined arc, in this case, a 90° arc.

The hollow plunger 8 is provided near its lower end with a pair of diametrically disposed ports 16 which register alternately with a port 17 provided in the plunger barrel 3.

A partition disc 18 is provided in the plunger 8 and forms a false top for the compartment defined by the hollow plunger. The partition disc 18 is equipped with a threaded stem 19 which extends upwardly through the stem 11, and is screw-threaded therein so that the partition disc 18 within the plunger 8 may be raised or lowered. A small bleeder passage is provided in the threaded stem 19. A lock nut 20 is provided on the projecting end of the stem 19 so that it may be locked in position. The partition disc 18 determines the effective volume of the plunger 8, that is, the partition disc 18 defines with the closed lower end of the plunger 8, a chamber of predetermined volume.

Secured to the under side of the table 1 in concentric relation with each plunger barrel 3 and extension 4 is a vacuum valve cage 21 in the form of a short cylinder of substantially larger diameter than the extension 4. The vacuum valve cage 21 reciprocally supports a vacuum valve 22 which is held against rotation relative to the cage 21 by key means 23. The vacuum valve is in the form of a disc with a flanged periphery riding in the cage 21, and is provided with a central plunger 24 equal in diameter to the hollow plunger 8. The plunger 24 projects into the extension 4 and is attached to the lower end of the hollow plunger 8 by means of a bolt 25. The plunger 24 is hollow, open at its lower end and closed at its upper end. Ports 26 and 27 are provided in the confronting ends of the hollow plunger 8 and the plunger 24, respectively. The ports 26 and 27 are closed when either of the ports 16 are in registry or in vertical alignment with the port 17 in the plunger barrel 3, and the ports 26 and 27 are adapted to register when the ports 16 are in right-angular relation with the port 17.

55 Springs 28 urge the vacuum valve 22 and conse-

quently, the plungers 24 and 8 toward their lower position, which position is the one in which the ports 16 and 17 occupy a common plane.

The lower end of the plunger 24 is provided with an annular lip 29 which defines the radially inner wall of a channel 30 formed in the under side of the vacuum valve 22. The channel 30 communicates through a vacuum port 31 to the periphery of the vacuum valve 22. The vacuum valve cage 21 is provided with a vacuum passage 32 terminating in a port 33 so located in the side wall of the valve cage 21 that when the vacuum valve is in its intermediate position shown in Fig. 2, the ports 31 and 33 register. The vacuum passage 32 communicates with a rotating annular vacuum shoe 34 which rides in an annular channel provided in the table 1. A stationary vacuum ring 35 rides in the vacuum shoe 34. Ports are so provided in the shoe 34 and ring 35 that the channel 33 is in communication with a source of vacuum pressure during a predetermined portion of the cycle of operation of the filling valve, as will be described hereinafter.

The bottom end of the vacuum valve 22 is provided with a sealing ring 36 formed of rubber or analogous material capable of forming a sealing contact with the upper edge or rim of a can C, or bottle or other container of food. The can or the like is carried on a platform 37. A stem 38 extends downwardly from the platform 37 and is equipped with a roller 39 which rides on an annular cam 40 having lower intermediate and upper steps 41, 42 and 43, respectively.

Operation of the filling apparatus is as follows:

The cans to be filled are fed from a suitable conveyor and transfer mechanism not shown, to a series of platforms 37 which are maintained under and in concentric registry with the vacuum valve 22 by means not shown. Initially, during movement of the platform on the lower step 41 of the cam, the can C clears the vacuum valve and the vacuum valve is in its lower position. This is the condition shown in Fig. 1. When the ports are in this lower position, one of the ports 16 is in registry with the port 17 so that liquid from the tank or vessel formed by the table 1 and wall 2, may flow into the measuring or metering compartment within the hollow plunger 8, filling the space between the lower end of the plunger 8 and the partition disc 18. In the condition shown in Fig. 1, the ports 26 and 27 are out of registry as are also the vacuum ports 31 and 33. When the platform 37 rides upon the intermediate step of the cam 40, the vacuum ports 31 and 32 register as shown in Fig. 2. During at least a portion of the time that the platform rides on the intermediate step of the cam, the vacuum passage 33 is in communication with the source of vacuum pressure so that the contents of the can are subjected to such vacuum pressure and air is withdrawn from the can and its contents. The ports 26 and 27 remain out of registry during this vacuumizing operation.

When the platform 37 rides upon the upper step 43 of the cam 40, the vacuum ports 31 and 33 no longer register, and preferably the vacuum passage 32 is cut off from the source of vacuum pressure. During the time that the platform 37 rides upon the upper step 43 of the cam, the spider wheel 12 engages the trip arm 15 to rotate the hollow plunger 8 relative to the lower plunger 24, bringing the ports 26 and 27 into registry. The vacuum created in the can and its contents, is maintained by reason of the fact that the port 31 is closed; consequently, the liquid is

drawn from the hollow plunger 8 not only by gravity, but by the vacuum pressure existing in the can and its contents.

After the liquid has discharged from the hollow plunger 8, the spider wheel may engage a second trip arm not shown, but similar to the trip arm 15 which rotates the upper plunger to its initial position in which the ports 26 and 27 are out of registry, but one of the ports 16 is in at least vertical alignment with the port 17. The remaining portion, not shown, of the cam 40 returns to its initial or lower step. An intermediate step similar to the step 42 may be provided to again bring the vacuum ports 31 and 33 into registry. At this portion of the cycle of operation, however, the vacuum passage 32 may be open to the air so that the vacuum existing above the liquid now contained in the can, may be released and the can freed from the sealing ring 36.

Many other embodiments of the invention may be resorted to without departing from the spirit of the invention.

I claim:

1. A filling apparatus comprising: a tank structure; a vacuumizing means under said tank structure, a reciprocable member adapted to effect sealing engagement with a container to be filled and adapted by its movement to effect communication between the interior of said container and a source of sub-atmospheric pressure; means defining a cylinder extending upwardly into said tank structure and having a lower open end communicating with the interior of said container; a hollow plunger means in said cylinder, including a lower part fixed to said reciprocable member, an upper relatively rotatable part, and valve means between said parts for discharging liquid from said upper part into said container; and other valve means between said upper part and the interior of said tank structure for admitting liquid into said upper part; said plunger means adapted by reciprocation and relative rotation of said upper and lower parts to control said valve means and thereby admit liquid into said upper part and thereafter discharge said liquid into said container sealed to said reciprocable member.

2. A construction as set forth in claim 1, wherein the upper part of said hollow plunger means includes a partition element adjustable therein to vary the effective volume of said upper part thereby to regulate the volume of liquid discharged into said container.

3. A filling apparatus, comprising: a tank structure including means defining a cylinder open at its lower end; a plunger structure reciprocable in said cylinder, and including a relatively rotatable upper plunger forming a measuring compartment and a lower plunger forming a container covering member adapted to effect sealing engagement with a container pressing upwardly thereagainst; reciprocable and rotatable valve means controlled by reciprocation and rotation of said measuring compartment relative to said cylinder means and container covering member to admit liquid from said tank structure into said measuring compartment and to discharge said liquid into a container sealed against said container covering member.

4. A filling apparatus, comprising: a tank structure including means defining a cylinder open at its lower end; a plunger structure reciprocable in said cylinder, and including a relatively rotatable upper plunger forming a measuring compartment and a lower plunger forming a container covering member adapted to effect sealing

engagement with a container pressing upwardly thereagainst; reciprocable and rotatable valve means controlled by reciprocation and rotation of said measuring compartment relative to said cylinder means and said container covering member to admit liquid from said tank structure into said measuring compartment and to discharge said liquid into a container sealed against said container covering member; a source of sub-atmospheric pressure, and means controlled by movement of said plunger structure to expose the interior of said container to said sub-atmospheric pressure source prior to discharge of said liquid therein.

5. A filling apparatus, comprising: a tank structure including means defining a cylinder open at its lower end; a plunger structure reciprocable in said cylinder, and including a relatively rotatable upper plunger forming a measuring compartment and a lower plunger forming a container covering member adapted to effect sealing engagement with a container pressing upwardly thereagainst; reciprocable and rotatable valve means controlled by reciprocation and rotation of said measuring compartment relative to said cylinder means and container covering member to admit liquid from said tank structure into said measuring compartment and to discharge said liquid into a container sealed against said container covering member; a valve device operable by reciprocation of said plunger structure to expose the interior of said container to vacuum pressure, said valve device adapted to be closed

prior to discharge of liquid into said container from said compartment.

6. A construction as set forth in claim 3, wherein in the upper plunger which forms said measuring compartment includes a partition element adjustable therein to vary the effective volume of said compartment thereby to regulate the quantity of liquid discharged into said container.

7. A construction as set forth in claim 5, wherein in the upper plunger which forms said measuring compartment includes a partition element adjustable therein to vary the effective volume of said compartment thereby to regulate the quantity of liquid discharged into said container.

15 8. A filling apparatus comprising: a sealing member adapted to seal the end of a container to be filled; means defining a measuring compartment carried on said sealing member; a first valve means between said measuring compartment and said sealing member adapted to discharge the contents of said compartment into said container; a second valve means at the lower end of said measuring compartment for admitting liquid to said measuring compartment; actuating means 20 for each of said valve means arranged to operate in sequence whereby liquid is first admitted to said compartment and later discharged into said container; and means for subjecting the interior of said container to vacuum pressure prior to opening of said valve means, said first seal means adapted to maintain the vacuum thereby created in said container until said valve means opens.

CLYDE D. RUSSELL.
